(57) **CLAIM**

I claim the ornamental design for a forearm for a rifle, as shown and described.

DESCRIPTION

FIG. 1 is a top perspective view of a forearm for a rifle showing my new design;
 FIG. 2 is an enlarged front elevational view thereof;
 FIG. 3 is an enlarged rear elevational view thereof;
 FIG. 4 is a left-side elevational view thereof, the right-side elevational view being a mirror image thereof;
 FIG. 5 is a top plan view thereof;
 FIG. 6 is a bottom plan view thereof; and,
 FIG. 7 is a bottom perspective view thereof.
